UNITED STATES PATENT OFFICE.

FIRMIN SMAL, OF COUTHUIIN, BELGIUM, AND CAMILLE TURQUOIS, OF PARIS, FRANCE.

CONTROL OF PETROL CARBUREATORS FOR AEROPLANE AND AIRSHIP ENGINES.

Application filed November 17, 1920. Serial No. 424,688.

(GRANTED UNDER THE PROVISIONS OF THE ACT OF MARCH 3, 1921, 41 STAT. L., 1313.)

To all whom it may concern:

Be it known that we, FIRMIN SMAL and CAMILLE TURQUOIS, subjects of the King of Belgium and of France, respectively, residing at Couthuin, Belgium, and Paris, France, respectively, have invented a new and useful Improvement in the Control of Petrol Carburetors for Aeroplane and Airship Engines (for which we have filed application in France Nov. 15, 1919, Patent No. 516,826, and in Belgium, Sept. 23, 1920), of which the following is a specification.

This invention relates to petrol carburetors for aeroplane engines, and greatly improves their working.

It is known, that such carburetors are provided with a suitable apparatus for correcting or regulating the carburetor, according to the different altitudes of the aeroplane.

Actually most of these apparatus are hand controlled.

The improvement, according to the present application, consists in an arrangement assuring the automatic working of such apparatus for regulating the carburetor by means of the varying pressure and temperature at the different heights.

As shown by the diagrammatic drawing, annexed as an illustration of the present invention, the arrangement comprises

1°.—Two pistons 1 and 2, without piston-rings and moving respectively in two single acting cylinders 3 and 4 in such a way that one side of each piston is in communication with the outside air.

2°.—A reservoir 5, said reservoir being of metal, air-tight, indissoluble and of good heat conductivity.

3°.—An airtight reservoir 6 of metal, placed between the two cylinders 3 and 4 and the reservoir 5, and filled with lubricating oil by the tube 7, the level of the oil in the reservoir 6 being kept constant by means of known regulating apparatus such as shown in the sketch, and comprising the float 9 and the needle-valve 8.

4°.—A tube 10 connecting the reservoir 5 to the reservoir 6 at a point above the constant oil level.

5°.—Two tubes 11 and 12 connecting respectively the two cylinders 3 and 4 to the reservoir 6 at a point below the constant oil-level.

6°.—A system comprising a lever 13 and

connecting rods 14 and 15 interconnecting the two pistons 1 and 2 in such a manner, that the whole will be equilibrated as far as gravity is concerned.

7°.—A rod 16 connected to the lever 13 and transmitting the motion of the two pistons 1 and 2 to the altimetric regulating apparatus of the carburetor.

8°.—A spring 17 regulating the movement of the pistons 1 and 2 whatever be their positions.

The plan of the drawings is that of the ground. The reservoir is here filled with atmospheric air at the same temperature and pressure as the outside air. As the flying machine rises, the atmospheric pressure on the pistons 1 and 2 and the temperature change, the temperature of the outside air being communicated by conductibility to the air contained in the reservoir 5, the volume of this reservoir remaining constant the inside air pressure must necessarily vary.

These variations in pressure and temperature of the exterior air cause consequently a to and fro motion of the pistons 1 and 2, said movement corresponding to the difference in pressure of the outside and the inside air of the reservoir 5, this latter pressure being communicated to the oil of the reservoir 6 which transmits said pressure to the pistons. The motion of the pistons 1 and 2 is suitably transmitted by the connecting rod 16 to the regulator of the carburetor.

It is shown above that the pressure of the air inside the reservoir 5 is transmitted to the pistons 1 and 2 by means of the oil of the reservoir 6. The particular working of this reservoir 6 constitutes one of the characteristics of this invention. Not only does the oil of the reservoir 6 transmit the pressure of the air contained in 5 to the pistons 1 and 2 but it serves also to lubricate said pistons and prevents the escape of air between the reservoir 5 and the atmosphere although the pistons have no rings the oil escaping between the pistons and the cylinders 3 and 4 being continuously replaced by the feeding pipe 7.

Further, the level of the oil remaining constant, the volume of the air contained in 5, 10 and that above the oil in 6 remains also constant, which is an essential and necessary condition for the good technical working of the whole system.

It should be noted that the diameter of the cylinders 3 and 4 is made sufficiently large in relation to that of the respective pistons 1 and 2 to allow the escape round 5 said pistons of any excess of oil in the system in order to avoid the oil-level rising when the atmospheric pressure increases; this escape of oil in excess does not offer any disadvantage provided the needle-valve 8 10 and the supply-pipe 7 are of sufficient size to allow the admission of oil at a rate sufficient to maintain the constant level in the tank 6 in any case and at any time.

On the contrary, it has been found in 15 practice that the more oil in excess escapes round the pistons, the better the apparatus works, the lubrication being thereby improved. It may be observed that the quantity of oil admitted by the needle valve is 20 immaterial as far as the operation of the apparatus is concerned, provided a rate of admission of oil exceeding the maximum amount which could escape is possible.

We claim:

25 An apparatus for automatically controlling a carburetor for aeroplanes, according to the changes in atmospheric pressure and temperature, due to different altitudes, said apparatus comprising an airtight reservoir,

30 filled with air, and communicating with another airtight reservoir, partially filled with air and partially with oil, the oil level being kept at a constant height by means of an oil feeding pipe and a suitable controlling device, such as a float combined with a 35 needle valve, the oil of the reservoir communicating by means of two tubes with a pair of cylinders in each of which moves a single acting piston, not provided with rings, and the free side of which is open to the 40 pressure of the outside air, the connecting rods of the pistons being attached respectively to the two arms of a lever pivoted at a point between its ends in such a way that the combination of pistons, levers and connecting rods is balanced, the two extremities of the lever being respectively attached, one to a reaction spring and the other to a suitable cable or rod connected with the altimetric correcting device of the carburetor. 45

50 In testimony thereof we signed hereunto our names in the presence of two subscribing witnesses.
